ABSTRACT OF THE DISCLOSURE

The improved washing machine of the present invention is particularly adapted for washing clothes and the like in wash water having a relatively high concentration of sudsable soap or synthetic detergent. The improved washing machine includes a rotatable, vertically disposed, inverted frusto-conical washing chamber positioned in, but spaced from, the walls of a stationary reservoir chamber. The lower, closed end of the reservoir chamber forms a wash reservoir. The upper open end of the washing chamber is substantially closed by a removable cover which includes means for introducing wash water into the interior of the washing chamber, means for permitting wash water to be removed from the washing chamber during high speed rotation of the washing chamber, and means for suppressing suds in the wash water removed from the washing chamber before the wash water is permitted to return to the reservoir. A suds shield is utilized to prevent suds from contacting the sides of the rotating washing chamber while the wash water is returning to the reservoir from the washing chamber. A rotating disc is positioned in the reservoir and is utilized to suppress suds formed in the wash water in the reservoir.

During operation, the washing chamber is rotated at a relatively high rotational speed about its vertical, central longitudinal axis so that the clothes and wash water in the washing chamber form an annular layer about the axis. Periodically, abruptly and briefly the rotational speed of the washing chamber is reduced to a rotational speed below that necessary to maintain the annular layer of clothes and wash water so that the clothes are tumbled and rearranged in the washing chamber. The rate of wash water being introduced and removed from the washing chamber is preselected so that during high speed rotation of the washing chamber, wash water in excess of that necessary to saturate the clothes is always present in the washing chamber.

BACKGROUND OF THE INVENTION

This invention relates to an improved washing machine for washing clothes and the like, and more specifically to an improved washing machine which is particularly adapted for washing clothes and the like in wash water having a relatively high concentration of sudsable soap or synthetic detergent and which is capable of significantly reducing the time and volume of water required for the washing operation while obtaining relatively superior cleaning action.

My United States Letters Patent Nos. 3,387,310 and 3,388,410, granted June 11, 1968 and June 18, 1968, respectively, disclose a significantly improved method of washing clothes and improved washing machines for performing this improved method. In summary, this improved method of cleaning clothes includes rotating the clothes and wash water in a washing chamber at a relatively high rotational speed so that the clothes and wash

2

water form an annular layer about the axis of rotation; periodically, abruptly reducing the rotational speed of the washing chamber to a speed below that necessary to maintain the annular layer of clothes and wash water in the washing chamber so that the clothes will be tumbled and rearranged in the washing chamber; and then again rotating the washing chamber at the relatively high rotational speed so that the annular layer of clothes and wash water is reformed. While the washing chamber is rotated at the relatively high speed, wash water is continuously forced over and through the clothes.

The use of the improved washing method disclosed in my aforementioned patents provides superior cleaning action relative to the cleaning action provided by present, commercially available machines, and in addition utilizes less time and wash water in the washing operation.

SUMMARY OF THE INVENTION

The improved washing machine of the present invention generally performs the improved method of washing clothes disclosed in the aforementioned patents, but has an improved design and structural arrangement, relative to the machines disclosed in the aforementioned patents and relative to the present, commercially available machines, that permits wash water having a relatively high concentration of sudsable soap or synthetic detergent to be used in the improved machine without excessive sudsing and the concomitant disadvantages of sudsing. Thus, the improved machine of the present invention includes the advantages of the machines disclosed in the aforementioned patents as well as permitting optimum cleaning action to be achieved as a result of the use of wash water having a high concentration of soap or synthetic detergent.

More specifically, the improved washing machine of the present invention includes a rotatable, vertically disposed, inverted frusto-conical washing chamber having a continuous side wall and a closed lower end. The washing chamber is positioned within a substantially congruent, stationary reservoir chamber. A wash water reservoir is defined in the lower end of the reservoir chamber beneath the lower end of the washing chamber, and the upper end of the side wall of the reservoir chamber extends above the upper end of the side wall of the washing chamber. The washing chamber is adapted to be rotated at a relatively high rotational speed about its central longitudinal axis so that the clothes and wash water in the washing chamber form an annular layer about the axis. Periodically, abruptly the rotational speed of the washing chamber is reduced to a speed below that necessary to maintain the annular layer of clothes and wash water so that the clothes are tumbled and rearranged in the washing chamber. Thereafter, the rotational speed of the washing chamber is again returned to the relatively high speed so that the annular layer is reformed. Wash water is continuously introduced into and removed from the washing chamber during the high speed rotation thereof.

The upper open end of the washing chamber is closed during operation of the washing machine by a removable cover so that any suds formed in the washing chamber are substantially contained in the washing chamber in that the suds can only flow out of the washing chamber through the small holes provided in the cover, and the passage through these holes effectively suppresses the suds. The cover includes a bottom wall and a plurality of annular side walls which define a central compartment

and radially inner and outer annular compartments. Wash water to be introduced into the rotating washing chamber is first introduced into the central and inner compartments with the major portion of the water being introduced into the central compartment. The central compartment communicates with a hose which extends toward the center of the washing chamber and is used to introduce wash water into the washing chamber from the central compartment. The inner compartment is adapted to hold soap or synthetic detergent and also functions as a lint trap. The inner compartment has a plurality of relatively small diameter holes in the adjacent bottom wall portion and in the side wall separating it from the outer compartment through which the water therein may pass into the washnig chamber and outer compartment, respectively.

The wash water removed from the washing chamber flows from the chamber into the outer compartment through a plurality of holes formed in the adjacent portion of the bottom wall of the cover. A plurality of holes are also formed in the outer peripheral side wall of the outer compartment. The water in the outer compartment is formed, by centrifugal force, to flow through these holes and the passage of water through these holes suppresses any suds entrained in the water. The holes in the bottom wall adjacent to the outer compartment are positioned relative to the upper end of the side wall of the washing chamber, so that the water removed from the chamber flows from the radially inner surface of the annular layer.

The wash water expelled from the outer compartment of the cover impinges against the side wall of the reservoir chamber and then runs down the side wall of this chamber into the reservoir. A suds shield is positioned between the side walls of the washing chamber and the reservoir chamber, and this shield prevents any suds formed during the passage of the water down the side wall of the reservoir chamber from contacting or causing "suds drag" on the rotating washing chamber.

An additional suds suppressing disc is positioned in the reservoir and rotates with the washing chamber. This suds suppressing disc includes a plurality of chambers which have perforated bottom and side walls through which the suds are forced to pass thereby suppressing the suds. Impeller blades are formed on the disc and are used to force the suds into the chambers.

Accordingly, it is a primary object of the present invention to provide an improved washing machine in which wash water having a relatively high concentration of soap or synthetic detergent may be used to achieve optimum cleaning results without excessive sudsing.

Another object of the present invention is to provide an improved washing machine of the type described wherein a rotatable, vertically disposed, inverted frusto-conical washing machine is positioned within, but spaced from the walls of a relatively stationary reservoir chamber wherein the washing chamber is adapted to be rotated at a relatively high speed about the central longitudinal axis of the washing chamber so that the clothes and wash water therein form an annular layer about the axis; wherein periodically, abruptly and briefly the speed of the washing chamber is reduced to a rotational speed below that necessary to maintain the annular layer of clothes and wash water so that the clothes are tumbled and rearranged in the washing chamber; wherein the washing chamber is again rotated at the high speed so that the annular layer of clothes and wash water is reformed; and wherein during high speed rotation, wash water is continuously introduced into and removed from the washing chamber.

Another object of the present invention is to provide an improved washing machine of the type described wherein the upper end of the washing chamber is closed by a cover so that suds formed in the washing chamber are contained within the chamber; wherein the cover in-

cludes means for introducing wash water into the interior of the washing chamber during high speed rotation, means for removing wash water from the chamber during high speed rotation and means for suppressing any suds entrained in the wash water removed from the washing chamber.

Still another object of the present invention is to provide an improved washing machine of the type described wherein a wash water reservoir is formed in the lower end of the reservoir chamber and beneath the lower end of the washing chamber; wherein the water removed from the washing chamber is expelled from the cover by centrifugal force, impinges against the upper end of the side wall of the reservoir chamber and thereafter runs down the side wall of the reservoir chamber and into the reservoir; wherein a suds shield is positioned between the side walls of the reservoir chamber and the washing chamber to prevent suds carried with the expelled water from contacting the rotating washing chamber; and wherein a suds suppressing disc is positioned in the reservoir and is rotated with the washing chamber so as to suppress suds in the reservoir.

These and other objects and features of the invention will become apparent from the following description of the preferred embodiment of the invention, taken in conjunction with the accompanying drawings.

DESCRIPTION OF THE DRAWINGS

FIG. 1 is a partial, vertical cross-sectional view of the improved washing machine of the present invention and also shows, schematically the electrical control system for the improved washing machine.

FIG. 2 is a partial, vertical cross-sectional view of the cover utilized in the improved washing machine of the present invention.

FIG. 3 is a partial, vertical cross-sectional view of the locking means utilized to retain the cover in the upper end of the washing machine of the present invention.

DESCRIPTION OF THE PREFERRED EMBODIMENT

Referring now to FIG. 1, the improved washing machine of the present invention is shown generally at 11. This improved machine includes an outer sheet metal cabinet 12 having top, side and bottom walls 13, 14 and 15, respectively. The top wall 13 has a central aperture which is normally closed by a hinged door 16.

A rotatable, vertically disposed, inverted frusto-conical washing chamber 17 is positioned within the housing 12 and includes a closed bottom end wall 18 and a continuous side wall 19 which is inclined outwardly from the bottom wall 18 at an angle of approximately fifteen degrees with respect to the vertical. An annular flange 21 extends generally radially inwardly, with respect to the central longitudinal axis of the chamber 17 and is secured to the upper end 22 of the side wall 19. The radially inner portion 23 of the flange 21 is bent so that it is positioned vertically and defines the periphery of a circular opening 24. A plurality of small diameter holes 25 are formed in the portion 23 for the purpose herein-after described.

A plurality of relatively small diameter holes 26 are formed in the flange 21 adjacent the upper end 22 of the side wall 19 of the chamber 17. These holes 26 are equi-spaced about the upper end 22, the wall 19 and are used to expel water from the washing chamber 17 during spin dry operation of the machine 11, although the wash water will, of course, flow therethrough at any time the chamber is rotated at high speed. However, the size and number of the holes 26 is such that the water expelled through these holes does not substantially affect the operation of machine 11, as described hereinafter, during the washing and rinsing operations.

The washing chamber 17 is supported for rotation about its central longitudinal axis by a power shaft 27.

More specifically, the upper end 28 of the power shaft 27 is attached to the center of the bottom wall 18 of the chamber 17 so that the central longitudinal axes of the power shaft and washing chamber are coaxial. The lower end 29 of the power shaft 27 is journaled in a bearing housing 29 secured to the bottom wall 15 of the cabinet 12.

The large diameter and small diameter sheaves 32 and 33 are positioned on the shaft 27 adjacent the lower end 29 thereof and are adapted to be connected with the shaft 27 by a pair of conventional, electrically actuated clutches 34 and 35, respectively. An example of a commercially available clutch which may be utilized to connect the sheaves 32 and 33 with the shaft 27 are the clutches manufactured by Stearns Electric Corporation of Milwaukee, Wis. The sheaves 32 and 33 are adapted to be driven by the V-belts 36 and 37, respectively.

A stationary, vertically disposed, inverted frusto-conical reservoir chamber 38 is also positioned within the cabinet 12 and has a shape generally congruent to the shape of the washing chamber 17. More specifically the reservoir chamber 38 includes a closed bottom end wall 39 and a continuous side wall 41 which is inclined outwardly from the bottom wall 39 at an angle of approximately fifteen degrees with respect to the vertical. The bottom wall 39 is positioned below the bottom wall 18 of the chamber 17 and the side wall 41 is spaced radially outwardly from the side wall 19 of the chamber 17, with the upper end 42 of the side wall 41 being positioned about the upper end 22 of the wall 19.

The bottom wall 39 of the reservoir chamber 38 has a central aperture formed therein through which the power shaft 27 projects. A conventional bearing and seal 43 is positioned about the shaft adjacent to the bottom wall 39 and is secured in place by the conventional bearing support 44.

A heavy frame 45 is utilized to support the reservoir chamber 38 within the cabinet 12 and to minimize the vibration of the chamber 38 during operation of the machine 11. More specifically, the frame 45 includes a plurality of spider arms 46 and base members 47 which are mounted on the bottom wall 15 of the cabinet 12. The upper ends of the arms 46 are fastened to the exterior surface of the side wall 41 of the chamber 38 at points spaced approximately midway between the upper and lower ends of the wall 41 and are equi-distant from each other. Heavy duty coil springs, two of which are shown at 49, are attached to and extend between the chamber 38, adjacent to the bottom wall 39, and the outer ends 51 of the base members 47.

A conventional shaft bearing 52 is positioned about and supports the shaft 27 adjacent its upper end 28. The bearing 52 is held in place by tubular arms, two of which are shown at 53, that extend through sealed apertures in the side wall 41 of the chamber 38 and are fastened to the arms 46 of the frame 45.

A conventional, two-speed electric motor 54 is mounted on one of the arms 46 of the frame 45. The motor 54 must be of the type which will permit the polarity of its windings to be reversed by changing the connections of the motor windings so that when the connections are changed, the motor will act as a brake. The output shaft 55 of the motor 54 has small diameter and large diameter sheaves 56 and 57, respectively, mounted thereon. The sheaves 56 and 57 receive the V-belts 36 and 37 and thus, by means of the V-belts, drive the sheaves 32 and 33, respectively.

The particular rotational speeds of the chamber 17 may vary depending on the size of the chamber and the weight of the clothes to be washed. In this connection, the intermediate speed is generally below 50 r.p.m. while the high speed rotation is generally above 60 r.p.m. and usually would be between 60-250 r.p.m.

A wash water reservoir 58 is formed in the bottom of reservoir chamber 38 below the bottom end 18 of the washing chamber 17. Hot and cold water, from sources

not shown, may be introduced into the chamber 58 through conduits 59 and 61, respectively. Electrically actuated valves 62 and 63 control flow through the conduits 59 and 61, respectively.

A conventional pump 64 is mounted adjacent to the bottom of the reservoir chamber 38 so that its inlet 65 communicates with the wash water in the reservoir 58. The pump 64 is driven by a conventional electric motor 66 through a conventional connection 67. The motor 66 is mounted on a support 68 which in turn is mounted on one of the arms 46 of the frame 45. The outlet 69 of the pump communicates with one end of a conduit 71 and the other end of the conduit 71 is positioned adjacent to the opening 24 in the upper end of the washing chamber 17. A first branch conduit 72 connects the conduit 71 with the reservoir 58, and a second branch conduit 73 connects the conduit 71 with a sump, not shown. Electrically actuated valves 74, 75 and 76 control the flow through conduits 71, 72 and 73, respectively, with the valve 74 being positioned in conduit 71 downstream from the points at which the branch conduits 72 and 73 are connected to the conduit 71.

Referring now to FIGS. 1 and 2, a generally circular cover 77 is shown positioned in and completely blocking the opening 24 formed in the upper end of the washing chamber 17. The cover 77, which may be made of plastic, includes a bottom wall 78 and three annular side walls 79, 81 and 82. The annular wall 79, together with the portion 83 of the bottom wall 78, defines a central compartment 84; the walls 79 and 81, together with an annular portion 85 of the bottom wall 78, define an inner annular compartment 86; and the walls 81 and 82, together with another annular portion 87 of the bottom wall 78, define an outer annular compartment 88. The height of the walls 79, 81 and 82 substantially equals the vertical height of the portion 23 of the flange 21 of the washing chamber 17.

An aperture 89 is formed in the portion 83 of the bottom wall 78, and the diameter of the aperture 89 is substantially equal to the diameter of the compartment 84. An annular flange 91 is formed on the bottom wall 78 between the portions 83 and 85 and extends a short distance below the plane of the bottom wall 78. The upper end 92 of a flexible hose 93 is positioned about the flange 91 and is secured in place by a conventional hose clamp 94. The hose 93 extends toward the bottom wall 18 from the cover 77 so that the water flowing therethrough is introduced into the interior of the washing chamber 17. The cover 77 is designed so that the central longitudinal axes of the central compartment 84, the aperture 89 and the hose 93 are coaxial with the central longitudinal axis of the washing chamber 17.

The portion 85 of the bottom wall 78 and the wall 81 have a plurality of relatively small diameter holes 95 formed therein. These holes 95 are smaller than the holes 25 formed in the portion 23 of the flange 21, and are of such a size that they may be used to filter lint and particles of dirt entrained in the water. A plurality of holes 96 are formed in the portion 87 of the bottom wall 78 and the side wall 82, and these holes have a diameter substantially equal to the diameter of the holes 25 formed in the portion 23 of the flange 21.

The cover 77 is secured within the opening 24 by three locks, one of which is shown generally at 97 in FIGS. 2 and 3. The lock 97 includes a central shaft 98 which has a knob or head 99 secured at one end thereof and which extends through a bore 101 formed in an integral projection 102 on the wall 82. The other end of the shaft 98 has an enlarged diameter portion 103 which has a small pin 104 projecting therefrom in a direction perpendicular to the central longitudinal axis of the shaft 98. When the cover is positioned, as shown in FIG. 2, the bore 101 is aligned with a bore 105 formed in the portion 24 of the flange. A groove 106, adjacent to the bores 101 and 105, is formed in the wall 82 and in the portion 24 and is designed to receive the pin 104. A light coil compression

spring 107 is positioned in the bore 101 between the portion 103 of the shaft 98 and a snap ring 108 secured in the radially inner end of the hub 102 and urges the shaft to the position shown in FIG. 3.

Rotation of the knob 99 through a ninety degree arc, from the position shown in FIG. 3, aligns the pin 104 with the groove 106 so that the shaft 98 can be retracted out of the bore 105, i.e., moved radially inwardly. When the shaft is thus retracted, relative movement between the cover 77 and the portion 23 of the flange 21 is possible and the cover 77 may be removed from the opening 24. Of course, when the knob 99 is released, the spring 107 causes the shaft 98 to move radially outwardly with respect to the wall 82 and into the bore 105, provided, of course, that the bores 101 and 105 are aligned, as shown in FIG. 3.

A plug 111 is utilized to block the end 109 of the conduit 71 which is adjacent to the opening 24. A pair of apertures 112 and 113 is formed in the end 109 with aperture 112 being positioned so as to permit wash water to flow therefrom into central compartment 84 and the aperture 113 being positioned so as to permit wash water to flow therefrom into the inner compartment 86. The size of the aperture 112 is greater than the size of aperture 113 so that the major portion of the wash water flowing through conduit 71 flows through aperture 112.

As noted above, the wash water from aperture 112 flows first into compartment 84 and then, through aperture 89 and hose 93, into the interior of the washing chamber 17. The wash water from aperture 113 flows first into compartment 86 and then flows through the openings 95 into the washing chamber 17. Because of the rotation of the chamber 17 and thus the cover 77, a portion of the wash water in compartment 86 flows through the holes 95 in the wall 81 into compartment 88.

Wash water also flows into compartment 88 through the holes 96 in the portion 87 of the bottom wall 78 of the cover 77 during high speed rotation of the chamber, i.e., during the time when an annular layer of wash water and clothes has been formed in the chamber. The holes 96 in the portion 87 are positioned, relative to the side wall 19 of the chamber 17, so that the wash water flowing into the compartment 88 is generally the water in the radially inner portion of the annular layer.

Because of the rotation of the cover, the wash water in compartment 88 is expelled from the compartment through the aligned holes 96 and 25 and impinges against the upper side wall 42 of the reservoir chamber 38. Thereafter, this water flows or runs down the side wall 41 into the reservoir 58.

A frusto-conical suds shield 114 is positioned substantially equi-spaced between the side wall 19 of the chamber 17 and the side wall 41 of the chamber 38 and is mounted on the side wall 41 by a plurality of brackets 115. The shield 114 prevents any suds in the wash water running down the side wall 41 from the contacting or causing "suds drag" on the rotating chamber 17.

To suppress sudsing in the reservoir, a disc 116 is mounted on and rotates with the power shaft 27 between the bearings 43 and 52. More specifically, the disc 116 includes a central hub 117 through which the power shaft 27 extends, with a conventional key and keyway 118 used to secure the hub 117 against rotation with respect to the shaft 27. The disc 116 also includes an annular side wall 119, a bottom wall 121, and four radially extending walls, two being shown at 122. These walls 119, 121 and 122, together with the hub 117, divide the disc 116 into four equal compartments, two of which are shown at 123. A plurality of holes 125 are formed in the walls 119, 121 and 122, and these holes are approximately the same diameter as the holes 25 formed in the portion 23 of the flange 21 of the chamber 17.

Formed integrally with the wall 122 are four blades or impellers, two of which being shown at 124, designed to direct or force the suds in the reservoir into the compartment

123. Any suds in the compartment 123 are forced, because of the rotation of the shaft 27 and thus the disc 116, through the holes 125 in the side wall 119, and the passage of the suds through these holes breaks down or suppresses the suds.

5 The operation of the motors 54 and 66, the clutches 34 and 35 and the valves 62, 63, 74, 75 and 76 are controlled by a timing mechanism which is shown schematically at 126. The timing mechanism 126 employs an electric motor which sequentially operates a plurality of switches in a preselected sequence. Such timing mechanisms are old and well known in the art, and for this reason further description of the mechanism 126 has not been included herein.

15

OPERATION

The operation of the washing machine 11 of the present invention is generally as follows:

The clothes or materials to be washed are placed in the interior of the washing chamber 17, and the cover 77 is 20 locked in place. Conventional soap or synthetic detergent may be placed in the inner compartment 86, and the wash water introduced into the compartment from the aperture 113 dissolves the soap or synthetic detergent. Alternatively, concentrated soap or detergent beads may be introduced directly into the reservoir 58 either manually or by 25 dispensing mechanism means, not shown. These beads may be similar to the beads produced by the bead producing machine and method disclosed in my United States patent application entitled "Machine and Method for Producing Laundry Products" filed Nov. 5, 1968, and identified in the United States Patent Office by Ser. No. 773,585. After the clothes and soap have been placed in the machine, the cover 16 is closed.

Either while the clothes are being placed into the washing chamber or after the loading of the clothes has been completed, the valves 62 and 63 are opened so that wash water may be introduced into the reservoir 58. Also, if 30 soap or detergent beads have been used, the motor 66 is energized, the valve 75 is opened, and the valves 74 and 35 76 are closed so that the wash water in the reservoir 58 is recirculated through the conduits 71 and 72 to insure 40 complete dissolving of the beads before the washing operation begins. After the loading has been completed and if used, the beads are completely dissolved, the motor 54 45 and the clutch 34 are energized so that the chamber 17 begins rotating at low speed. At the same time, the valve 74 is opened and valve 75 is closed so that wash water 50 flows through conduit 71 and into the chamber 17. After a sufficient volume of water has been pumped into the 55 washing chamber 17, i.e., in excess of that necessary to saturate the clothes in the washing chamber, the clutch 34 is de-energized, the clutch 35 is energized, and the motor 54 is operated at its higher speed so that the chamber 17 begins rotating at the relatively high rotational speed whereby the clothes and wash water in the chamber 17 form an annular layer about the central longitudinal axis of the chamber.

While the chamber is rotating at the relatively high speed, the wash water is continuously introduced into the 60 chamber through the hose 93 and the holes 95 formed in the portion 85 of the bottom wall 78 of the cover 77. As noted above, water is continuously removed from the chamber 17 during high speed rotation of the chamber through the holes 96 formed in the portion 87 of the 65 bottom wall 78 of the cover 77. The water in the compartment 88 is expelled almost immediately from the compartment through the aligned holes 96 and 25, and the passage of the water through these holes suppresses any suds entrained in the water so that the expelled water 70 impinging upon the side wall 41 of the chamber 38 is substantially suds free.

As the water runs down the side wall 41, the suds shield 114 prevents any suds from contacting or "dragging" 75 against the rotating chamber 17. When the water returns to the reservoir 58, the disc 116 suppresses any suds

formed therein. More specifically, any excessive suds in the reservoir are forced by the impellers 124 into the compartments 123, and the passage of the suds through the holes 125 in the wall 119 breaks down or suppresses the suds. The wash water in the reservoir is again pumped back into the chamber, and because of this continuous recirculation of the water, a very small volume of water is present in the reservoir at any time.

Periodically, abruptly during the washing operation, the clutch 35 is de-energized, the clutch 34 is energized and the motor 54 is braked and then operated at its lower speed so that the speed of the rotating chamber is abruptly reduced from the relatively high rotational speed to a rotational speed below that necessary to maintain the annular layer of clothes and wash water in the chamber. Since at least part of the clothes will have "climbed" up the side wall 19 of the chamber during high speed rotation thereof, the clothes are tumbled and rearranged in the chamber as a result of their falling away from the side wall when the speed of the chamber is abruptly reduced. After such an abrupt reduction of speed, the clutch 35 is again energized, the clutch 34 is de-energized and the motor 54 operated at its high speed so that the chamber again rotates at high speed and the annular layer of clothes and wash water is reformed. This washing cycle, i.e., forming an annular layer of clothes and wash water, tumbling and rearranging the clothes by reducing the speed of the chamber and then reforming the annular layer, is repeated a number of times during the washing operation.

After the washing operation has been completed, the valve 74 is closed and the valve 73 is opened so that the pump 64 pumps the water in the reservoir 58 to the sump. Thereafter, clean rinse water can be introduced into the reservoir through the conduits 59 and 61 with the valve 74 opened and the valve 73 closed. The rinsing operation is substantially the same as the washing operation except that, of course, there is no soap or synthetic detergent added to the water. After the rinsing operation has been completed, the rinse water is pumped to the sump through the branch conduit 73 and the chamber 17 is rotated at the relatively high speed so as to spin dry the clothes. The openings 26 permit the water remaining in the chamber 17 and in the clothes to be expelled out of the chamber during the spin dry operation. As noted above, the size and number of the openings 26 are sufficiently small so that the flow of water through the openings 26 does not substantially affect the above described operation of the machine 11 during the washing and rinsing cycles.

A more specific example of the times required to perform typical washing, rinsing and spin drying operations in a washing machine embodying the present invention is set forth in Table 1 hereinbelow. The washing machine used for the cleaning operations described in Table 1 includes a washing chamber having a mean tub diameter of 18 inches and a depth of 17 inches and with the side wall of the chamber sloping at an angle of 15 degrees. Approximately sixteen pounds of clothes (dry weight) are placed in the rotating chamber, and at any given time during the high speed rotation of the chamber, there are between 28 and 68 pounds of wash water plus 32 pounds of saturated clothes in the chamber, i.e., 16 pounds of clothes and 16 pounds of water to saturate the clothes. Wash water is recirculated in the machine at the rate of about 15 gallons per minute or approximately 1.45 pounds per second due to the aeration of the wash water by the pump.

The high speed of the chamber is 100 r.p.m. while the intermediate or reduced speed is 45 r.p.m. The machine utilizes a $\frac{3}{4}$ H.P. electric motor, corresponding to motor 54, that can accelerate the washing chamber from 45 r.p.m. to 100 r.p.m. in about four seconds. The washing chamber can be braked from 100 r.p.m. to 45 r.p.m. in about two seconds.

Steps		Time, seconds	Water, in pounds			Recirculating
			In	Out	In system	
5	Clothes in:					
	Partial fill, at 45 r.p.m.	60	60	-----	60	1 44
	Speed-up to 100 r.p.m.	4	4	-----	64	48
	Wash cycle number 1:

¹ 16 lbs. clothes.

² Or 10.9 minutes.

30 By calculation, it has been found that a washing machine of the present invention can provide approximately thirty-four times the amount of relative movement between the clothes and wash water as can be provided by conventional agitator type washing machines operating at 100 cycles per minute and moving the clothes three inches on each stroke, in both directions, of the agitator. Moreover, the total time for the complete washing operation in the washing machine of the present invention may be as little as one-half the time required for the same cleaning operation in commercially available washing machines.

35 As noted above, one of the advantages of the improved washing machine of the present invention is that it can use wash water having a relatively high concentration of soap or synthetic detergent without having any problems with excessive sudsing. In addition and as compared with the washing machines disclosed in the aforementioned patents using the same wash water, the improved washing machine of this invention requires relatively less power to operate. This results because the washing chamber 17, with the cover 77, is effectively a closed container with respect to the suds formed in the washing chamber, i.e., suds can only escape from the chamber 17 through the holes 96 and 25 which suppress the suds. Therefore, although the washing chamber could be rotated at a sufficiently high speed, i.e., above 300 r.p.m., so that no suds could be formed in the chamber, the chamber 17 does not need to be rotated at that high a rotational speed. In fact, the chamber 17 may be rotated at a "lower" high speed, i.e., a speed just high enough to form an annular layer of clothes and wash water, since even if some suds are formed in the chamber 17, these suds will not cause any particular problem. Thus, because the washing chamber 17 is effectively closed, the machine 11 can rotate at a "lower" high speed and this, of course, conserves power, particularly in view of the frequent changes in the rotational speed of the chamber 17 during the washing and rinsing operations.

40 45 50 55 60 65 70 75 75 Thus, in view of the foregoing, it will be apparent that the improved washing machine of the present invention enables clothes and the like to be thoroughly cleaned in a relatively short period of time as compared with present commercially available machines. Moreover, the improved washing machine of the present invention permits the use

11

of wash water having a relatively high concentration of soap or synthetic detergent which, of course, promotes cleaning while suppressing the detrimental sudsing of the wash water.

Also, it should be noted that various modifications may be made in the improved washing machine of the present invention described herein above. For example, the specific design and arrangement of the cover may be modified; and in fact, it is contemplated that as the size of the washing chamber varies, the size and arrangement of the holes in the cover 77, and particularly the holes 96 in the portion 87 of the bottom wall 78, will be varied in size and spacing. Of course, it would also be obvious that other means could be used to secure the cover 77 within the opening 24 and that the angle of inclination of the side walls of the washing and reservoir chambers may be varied although it is believed that the angle of 15 degrees is an optimum angle. Likewise, the frame utilized to support the reservoir chamber 38 may be modified as well as the positioning and the arrangement of the bearings journaling the power shaft 27. For this reason, the preferred embodiment of the present invention described hereinabove is therefore to be considered in all respects as illustrative and not restrictive, the scope of the invention being indicated by the appended claims, rather than by the foregoing description. And all changes which come within the meaning and range of equivalency of the claims are therefore intended to be embraced therein.

I claim:

1. An improved machine for cleaning clothes and the like in wash water having a relatively high concentration of a sudsable soap or synthetic detergent, comprising:

a rotatable washing chamber which is positioned so that its central longitudinal axis is substantially vertical, which includes a closed lower end, a substantially open upper end and a side wall, and which is adapted to receive the clothes to be washed and wash water; means for rotating the washing chamber about said central longitudinal axis at a relatively high speed so that the clothes and wash water form an annular layer about said central longitudinal axis and adjacent the side wall of the washing chamber; means for periodically, abruptly reducing the rotational speed of the washing chamber to a rotational speed below that necessary to maintain said annular layer of clothes and wash water so that the clothes are tumbled and rearranged in the washing chamber; means for supplying wash water to the washing chamber during said relatively high speed rotation of the washing chamber;

means for removing wash water from the washing chamber during said relatively high speed rotation of the washing chamber; and

means rotatable with the washing chamber for suppressing the suds in the wash water removed from the washing chamber.

2. The improved machine described in claim 1 wherein the washing chamber has an inverted, frusto-conical shape; and wherein the side wall of the washing chamber is continuous and inclined with respect to said central longitudinal axis.

3. The improved machine described in claim 1 and means for continuously introducing into and removing wash water from the washing chamber at predetermined rates during said relatively high speed rotation of the washing chamber so that wash water in excess of that required to saturate the clothes is present in the washing chamber during the relatively high speed rotation of the washing chamber.

4. The improved machine described in claim 1 wherein the means for abruptly reducing the rotational speed of the washing chamber quickly returns the washing chamber to said relatively high speed so that the clothes and wash water again form an annular layer about said central longitudinal axis of the washing chamber.

12

5. The improved machine described in claim 1 wherein said means rotatable with the washing chamber for suppressing the suds in the wash water includes cover means positioned in said upper end of the washing chamber so as to substantially close said upper end and to substantially confine any suds formed in the washing chamber in the washing chamber.

6. The improved machine described in claim 5 wherein the cover means includes a central compartment, and radially inner and outer annular compartments which are separated by an annular wall; wherein the wash water to be supplied to the washing chamber is introduced into the central compartment and into the inner compartment; wherein a flexible conduit communicates with the central compartment and extends from the central compartment toward the center of the washing chamber so that the wash water in the central compartment flows through the conduit and into the washing chamber; and wherein the cover means also includes a plurality of relatively small diameter holes which permit the wash water to flow from the inner compartment into the washing chamber.

7. The improved machine described in claim 5 wherein the cover means includes a central compartment, and radially inner and outer annular compartments which are separated by an annular wall; and wherein the cover means includes a plurality of holes which are arranged, in relation to the side wall of the washing chamber, so as to permit wash water to flow from the washing chamber into the outer compartment during said relatively high speed rotation of the washing chamber.

8. The improved machine described in claim 7 wherein said plurality of holes in the cover means for permitting wash water to flow from the washing chamber into the outer compartment are spaced radially inwardly with respect to the upper end of the side wall of the washing chamber.

9. The improved machine described in claim 7 wherein the wash water to be supplied to the washing chamber is introduced into the central compartment and into the inner compartment; wherein a flexible conduit communicates with the central compartment and extends from the central compartment toward the center of the washing chamber so that the wash water in the central compartment flows through the conduit and into the washing chamber; and wherein the cover means also includes a plurality of relatively small diameter holes which permit the wash water to flow from the inner compartment into the washing chamber.

10. The improved machine described in claim 9 wherein the annular wall has a plurality of relatively small diameter holes therein whereby a portion of the wash water in the inner compartment is forced, as a result of the rotation of the washing chamber, to flow into the outer compartment during rotation of the washing chamber; and wherein the side wall of the outer compartment includes a plurality of holes whereby the wash water in the outer compartment is forced, as a result of the rotation of the washing chamber, to flow from the outer compartment during rotation of the washing chamber, said holes in the side wall of the outer compartment being arranged and of such a size so that the passage of wash water through said holes suppresses suds in the wash water.

11. The improved machine described in claim 10 wherein wash water is continuously introduced into and removed from the washing chamber during said relatively high speed rotation of the washing chamber; and wherein the rates of introduction and removal of wash water are predetermined so that wash water in excess of that required to saturate the clothes is present in the washing chamber.

12. The improved machine described in claim 1 wherein a relatively stationary reservoir chamber, having a closed lower end, a side wall and an open upper end, is positioned about the washing chamber so that the upper end

of the reservoir chamber extends above the upper end of the washing chamber, so that the lower end of the washing chamber is spaced above the lower end of the reservoir chamber and so that the side wall of the washing chamber is spaced from the side wall of the reservoir chamber.

13. The improved machine described in claim 12 wherein a suds shield is positioned between the side walls of the washing chamber and the reservoir chamber to prevent suds on the side wall of the reservoir chamber from contacting the side wall of the rotating washing chamber.

14. The improved machine described in claim 13 wherein in both the washing chamber and the reservoir have an inverted, frusto-conical shape; wherein the suds shield is frusto-conical in shape; and wherein the side walls of both the washing chamber and the reservoir chamber are continuous and are inclined with respect to the central longitudinal axis of the washing chamber.

15. The improved machine described in claim 12 wherein in a wash water reservoir is defined in the lower end of the reservoir chamber; and wherein a wash water pump is positioned so that its inlet is connected with the reservoir and its outlet is connected with central and inner compartments of the cover means, the pump having a pumping capacity at least equal to the flow rate of the wash water being removed from the rotating chamber so that a minimal volume of wash water is maintained in the reservoir.

16. The improved machine described in claim 15 wherein in a power shaft for rotating the washing machine is connected to the lower end of the washing chamber and extends vertically through the lower end of the reservoir chamber; and wherein suds suppressing means rotates with the power shaft in the reservoir.

17. The improved machine described in claim 16 wherein in the suds suppressing means includes an annular chamber defined by perforated bottom and side walls, and vane means which are utilized to force suds in the upper portion of the reservoir into said annular chamber during rotation of the suds suppressing means.

18. The improved machine described in claim 17 wherein in wash water is continuously introduced into and removed from the washing chamber during said relatively high speed rotation of the washing chamber; and wherein the rates of introduction and removal of wash water are predetermined so that wash water in excess of that required to saturate the clothes is present in the washing chamber.

19. The improved machine described in claim 18 which includes cover means positioned in said upper end of the washing chamber so as to substantially close said upper end and to substantially confine any suds formed in the washing chamber in the washing chamber; wherein the cover means includes a central compartment, and radially inner and outer compartments which are separated by an annular wall; and wherein the cover means includes a plurality of holes which are arranged, in relation to the side wall of the washing chamber, so as to permit wash water to flow from the washing chamber into the outer annular compartment during said relatively high speed rotation of the washing chamber.

20. The improved machine described in claim 19 wherein in said plurality of holes in the cover means for permitting wash water to flow from the washing chamber into the radially outer compartment are spaced radially inwardly with respect to the upper end of the side wall of the washing chamber.

21. The improved machine described in claim 20 wherein in the wash water to be supplied to the washing chamber is introduced into the central compartment and into the inner compartment; wherein a flexible conduit communicates with the central compartment and extends from the central compartment toward the center of the washing chamber so that the wash water in the central compartment flows through the conduit and into the washing chamber; and wherein the cover means also includes a plurality of relatively small diameter holes which permit the wash water to flow from the inner compartment into the washing chamber.

22. The improved machine described in claim 21 wherein in the annular wall has a plurality of relatively small diameter holes therein whereby a portion of the wash water in the inner compartment is forced, as a result of the rotation of the washing chamber, to flow into the outer compartment during rotation of the washing chamber; and wherein the side wall of the outer compartment includes a plurality of holes whereby the wash water in the outer compartment is forced, as a result of the rotation of the washing chamber, to flow from the outer compartment during rotation of the washing chamber, said holes in the side wall of the outer compartment being arranged and of such a size so that the passage of wash water through said holes suppresses suds in the wash water.

23. The improved machine described in claim 22 wherein in the means for abruptly reducing the rotational speed of the washing chamber quickly returns the washing chamber to said relatively high speed so that the clothes and wash water again form an annular layer about said central longitudinal axis of the washing chamber.

24. The improved machine described in claim 22 wherein in a plurality of relatively small diameter holes are formed in the upper end of the side wall of the washing chamber so that wash water is expelled from the washing chamber through said holes during said relatively high speed rotation and during the speed changes of the washing chamber.

25. The improved machine described in claim 22 wherein in both the washing chamber and the reservoir chamber have an inverted, frusto-conical shape; and wherein the side walls of both the washing chamber and the reservoir chamber are continuous and are inclined with respect to said central longitudinal axis of the washing chamber; and wherein the cover means is removable from said upper end of the washing chamber so as to permit insertion and removal of the clothes into and from the washing chamber.

26. The improved machine described in claim 25 wherein in a frusto-conical shield is positioned between the side walls of the washing chamber and the reservoir chamber to prevent any suds on the side wall of the reservoir chamber from contacting the side wall of the rotating washing chamber.
